CUSHION CONSTRUCTION

Henry Hopkes, Grosse Pointe, Mich., assignor to
No-Sag Spring Company, Detroit, Mich., a corporation of Michigan

Application November 9, 1936, Serial No. 109,897

2 Claims. (Cl. 155—179)

This invention relates in general to an improved spring frame and cushion construction and, in particular, to spring frame and cushion constructions for furniture seats, backs or the like.

The main objects of the invention are: to provide a spring cushion construction having an unobstructed, free spring front edge; to provide a simplified spring cushion construction in which the wire for supporting the spring elements forms the frame for the cushion; to extend the side portions of a spring frame to form supports therefor; to provide a downwardly disposed brace between the side portions of the spring frame to brace the sides and form a further support for the frame; to provide a tacking frame to which said frame deflected and supporting portions are secured; to provide a frame having its front portion bent downwardly to form a support and to provide an unobstructed front edge for the springs which span the frame sides; to provide a spring surface having the elements closely disposed to provide small gaps so that a thin pad may be supported thereon without materially projecting therethrough; and, in general, to provide a seat frame and cushion, which is simple in construction and economical of manufacture.

Other objects and features of novelty of the invention will become apparent from the following specification, from the claims hereinafter set forth, and from the drawings, in which like numerals are used in the several views to designate like parts, and wherein:

Figure 1 is a side elevational view of a seat, with parts broken away, illustrating a spring cushion construction embodying the invention;

Fig. 2 is a top plan view, with parts broken away, showing an embodiment of the spring frame construction of the seat illustrated in Fig. 1;

Fig. 3 is a front elevational view of the spring frame construction shown in Fig. 2;

Fig. 4 is a side elevational view of the spring frame construction shown in Figs. 2 and 3;

Fig. 5 is an enlarged, sectional view, taken along line 5—5 of Fig. 2, showing the channel in the border wire;

Fig. 6 is an enlarged, sectional view, taken along the line 6—6 of Fig. 2, illustrating the manner in which the ends of the spring elements are attached to the border wire.

Fig. 7 is a perspective view with parts broken away, showing a further form which my invention may assume, and

Fig. 8 is an enlarged broken view of a portion of the chair illustrated in Fig. 7.

In Fig. 1, a seat is illustrated comprising a base frame 10, a border wire 12 and a spring surface 14 interrelated to produce my novel spring frame construction. The spring surface 14 is constructed to provide small gaps between the wire elements to form a plane surface on which a thin sponge rubber pad 16 may be supported. The frame and pad may then be covered by suitable trim material 18, in a well known manner.

In Figs. 2 to 5, I have illustrated the base frame 10 as being made of wood strips 20, 22, 24 and 26. The base frame forms the support for the cushion frame and a medium into which tacks for securing the trim material, are driven. Other frame known in the art to be suitable, may be utilized in place of the frame 10, which is shown for the purpose of illustration.

The spring surface 14 is disposed in an arcuate plane spaced from the base frame 10 in a manner to be later more fully described. The surface is constructed from a plurality of spring elements 28 of the type disclosed in the Kaden Patent No. 2,002,399, issued May 21, 1935 and under which the applicant's assignee is an exclusive licensee. Spring elements of this type are formed by sinusously bending a suitable spring wire and curving the sinusous wire longitudinally of its length to provide a set therein on an arc materially less than the arc it assumes when employed in a seat.

The ends of the elements are spread and secured in arched position to have the unsecured portion between the ends provided with a tension to resist downward displacement. The spring surface 14 is formed from a plurality of like spring elements 28, 29, 30, 31 and 32. The spring elements are mounted in spaced parallel relation to each other crosswise of the seat to obtain a soft front edge as will be more fully described.

The spring elements are connected at their ends to the side portions 34 and 36 of the border wire 12, which has a channel 37 on its inner side for receiving the laterally extending end of each of the spring elements. The spring elements are secured in place in the border wire by a crimping operation which secures the outer edges of the channel over the ends of the elements, as indicated at 38 in Fig. 6. The spring elements are of such length and are secured in such positions that they will assume the proper curvature or bolster for the surface of the seat. The inherent tendency of each of the spring elements is to assume an arc of smaller radius and the elements will thereby offer resistance to downward displacement. The spring elements are positioned

to lie in the same curved plane forming a very thin resilient spring structure.

The spring frame constructed in this manner is supported in order to provide front side supports for the spring elements at its forward or front edge by the portions 40 and 42 of the border wire 12, which is bent downwardly and sloped rearwardly and joined at their lower ends by the cross portion 43. The portion 43 is secured to the frame by straps 44 and 46 of metal or other material by suitable screws 48 and 50, respectively. The border wire not only supports the spring elements but forms the spacing means for the spring surface 14 and frame 10 and when so deflected provides the unobstructed spring front edge to the spring surface.

The rear portion 52 of the border wire may be provided with a Z-shaped plate 54 having its upper projecting portion disposed in the channel 37 and welded, clinched or otherwise secured therewith with the bottom projecting portion provided with an aperture to receive a securing screw 56. While a single plate 54 is illustrated, it is to be understood that a plurality could be employed, spaced along the edge of the border wire 12. When the wire is not deflected to provide the soft front edge for the cushion, the wire may be entirely supported by the plates.

Additional support may be provided by a central bracing element 58 which is herein illustrated as being similar in cross section to the border wire 12. The bracing element 58 is bent upwardly at its ends, as indicated at 68 and 70, to receive wires 72 and 74, respectively, of the border wire 12. Straps 60 and 62, similar to straps 44 and 46, secure the bracing element 58 to the frame 10 by suitable screws 64, 66. The bracing element 58 prevents the movement of the portions 34 and 36 of the border wire 12 and aids in securing the wire to the base frame.

In Figs. 7 and 8 I have shown a further form which my invention may assume. In Fig. 7, a chair is illustrated, comprising tubular frame 71, joined at the rear by tubular elements 72. A cushion 73 is supported by the tubular frame 71 and elements 72, forming a back for the chair. A seat frame 73 is also supported by the tubular frame and elements and is herein illustrated as having a front portion 74 cut away at 75 at its top edge. Joined to the front portion 74 is a rearwardly disposed U-shaped portion 76, the extending legs of which form a support for the spring elements 77. The elements 77 are similar to those described heretofore relative to the structure illustrated in Figures 1 to 6, inclusive. The elements 77 have their ends secured by clips 78 to the extended legs of the U-shaped seat

portion 76. In view of the cut-away section of the frame portion 75, the spring elements 77 form a soft front edge to the seat which will not bottom. A suitable pad 81 which may be of felt or rubber, as hereinbefore pointed out, is disposed upon the spring elements 77 and a suitable trim cover material 82 is disposed over the pad. A very substantial seat is provided in this manner which has a soft front edge and which is very light in weight.

One of the features of this invention is the provision of a spring surface in which all portions of the spring elements lie in substantially the same plane. The elements forming the surface are of the flat sinuous type and provide a support for a pad in which a maximum contact area is provided. The closely adjacent portions of the spring elements make it possible to employ a very thin sponge rubber pad which was not possible with prior spring constructions since sufficient contact support was not provided. The thin sponge rubber pad 16 supported on the spring surface 14 having its front edge unsupported, provides a very comfortable seat, one which is relatively inexpensive to manufacture. It is to be understood that a similar construction can be employed for forming a back cushion for the seat cushion herein described.

While I have described and illustrated but a single embodiment of my invention, it is to be understood that formal changes may be made therein without departing from the spirit and substance of the broad invention, the scope of which is commensurate with the appended claims.

I claim as my invention:

1. A seat embodying a border element of U-shape having portions at the open end extending downwardly forming supports, spring elements spanning the sides of said border element and retained thereby to form a spring surface having an unobstructed front edge, and a brace extending below said border element and secured to the side portions thereof to provide rigidity thereto.

2. A seat embodying a border element of U-shape having portions at the open end extending downwardly forming supports, spring elements spanning the sides of said border element and retained thereby to form a spring surface having an unobstructed front edge, a brace extending below said border element and secured to the side portions thereof to provide rigidity thereto, and a tacking frame to which said downwardly projecting portions of the border element and the bracing element are secured.

HENRY HOPKES.
